CLAIM

The ornamental design for a water-powered brush, as shown and described.

DESCRIPTION

FIG. 1 is a front elevational view of a water-powered brush showing my new design;

FIG. 2 is a rear elevational view thereof;

FIG. 3 is a side view, taken from the left side of FIG. 1;

FIG. 4 is a side view, taken from the right side of FIG. 1;

FIG. 5 is a top plan view thereof;

FIG. 6 is a bottom plan view thereof; and,

FIG. 7 is a reduced perspective view thereof.

The broken line showing a sink and faucet in FIG. 7 is for illustrative purposes only and forms no part of the claimed design.

The hose portion is shown broken away in FIGS. 1, 2, 5, and 6 for ease of illustration.
